CURLER

Joseph Keith O'Moore Farrell, London, England

Application January 18, 1946, Serial No. 641,996
In Great Britain January 29, 1945

9 Claims. (Cl. 132—34)

1

This invention relates to curlers for use in curling hair.

An object of the invention is to provide a device whereby the hair may be gripped at its end and wound into a curl on one part of the device, the curl then being gripped between parts of a clip forming a separable part of the device and the other part of the device being readily removable from the coil.

Another object of the invention is to provide a device comprising a hair clip adapted to co-operate with but separable from a cylindrical member on which a curl may be wound, this cylindrical member comprising means for gripping the hair before beginning to wind.

Other objects of the invention will be apparent from the following description of one form which is given by way of example.

In the drawing:

Fig. 1 is a longitudinal section of the device with the clip portion separated from the winding portion,

Fig. 2 is an end elevation of the winding portion in the direction of the arrow II,

Fig. 3 is a longitudinal section of the device with the two parts in co-operative relationship,

Fig. 4 is a view of a modified form of clip which may be used with the winding portion shown in Fig. 1, and

Fig. 5 is a view of the clip shown in Fig. 4 when opened.

The device comprises two separable parts, a winding part 1 and a clip part 2. The winding part comprises a cylindrical tube 3 which at one end is cut away on each side to form jaws 4.

Rotatably mounted in the other end is a plug 5 which may be of wood or a synthetic moulding material and which for greater strength is enclosed in a casing 6. The plug 5 is formed with a spigot 7 on which is fixed a knob 8, whereby the plug 5 may be rotated in the tube 3.

Fixed in the plug 5 and eccentrically disposed with regard to the tube 3 is a rod 9. This rod 9 extends through the tube 3 and slidably mounted on it is a tube 10. Separation of the tube 10 and the rod 9 is prevented by a projection 11 on the rod and the inturned end 12 of the tube 10.

It will be seen that if the end of a tress of hair is inserted between the jaws 4, and the plug 5 is rotated by the knob 8, the eccentric movement of the rod 9 will cause the hair to be gripped between the tube 10 and the inner surface of one or other of the jaws 4.

The clip portion 2 of the device comprises a pin 13 which is hinged to a clasp member 14 which

2

is relatively wide. This clasp member may be formed by bending a wire of substantially the same diameter as the pin 13 into an open substantially rectangular shape, a U-shaped dent 15 being formed in the nose of the clip. The pin 13 and the member 14 are hinged together so that they may be opened out as shown in Fig. 1 or can be closed so that the pin 13 is pressed towards the member 14 to grip the hair of a curl between them. This hinge arrangement may be of any conventional form; as shown one end 16 of the wire forming the member 14 forms a pivot for the pin 13 and the other end 17 of the wire forms a spring which in the closed position of the grip bears against a projection 18 of the pin 13.

Fixed to the free end of the pin 13 is a tube 19 of such internal dimensions that it can be slipped over the tube 10 of the winding part 1. When the clip is closed, this tube 19 rests in the U-shaped dent 15.

To use the device, the tube 10 is extended on the rod 9 and the tube 19 slipped over it, the clip 2 then being in the open position as shown in Fig. 1. The clip 2 is then pushed towards the winding portion 1 so that the tubes 10 and 19 slide along the rod 9 and come between the jaws 4.

The end of the tress of hair is then inserted between the jaws 4 and the knob 8 is rotated relatively to the cylindrical tube 3 so that the hair is gripped tightly between the inner surface of one of the jaws 4 and the tube 19. The curl is then formed by rotating the whole device so as to wind the hair around the tube 3.

When the curl has been formed, the clip is closed by turning the member 14 over on to the hair. The winding portion can then be detached by pulling it lengthwise from the curl, the tube 19 slipping out of the tube 10 and the curl remaining gripped by the clip.

The clip shown in Figs. 4 and 5 has the pin 20 and the co-operating clamping member 21 formed from a single piece of wire, the two parts being connected by a circular portion 22 forming a spring. The member 21 is bent as shown to provide a relatively wide clip. The pin 20 has a tube 23 riveted or otherwise fixed to its end and is used this tube co-operates with the tube 10 of the winding part 1 in the manner already described. The part 21 is formed with a U-shaped recess 24 to receive the tube 23 in the closed position of the clip.

A wedge 25 rests, in the closed position of the clip in the circular portion 22 and can be moved between the pin 20 and the member 21 to force

these parts away and open the clip. The clip is in this manner retained in the open position whilst the curl is being wound. By pushing the wedge back into the circular portion, the clip is closed.

The wedge 25 is formed with grooves 26 at each end which engage with the arms of the member 21 and guide the wedge in its movement to open or close the clip.

It will be apparent that many modifications may be made in the details of the forms described within the scope of the appended claims.

I claim:

1. A curler comprising a cylindrical tube formed with jaws at one end, a member eccentrically mounted in the tube and rotatable about the axis thereof between the jaws, a tube portion slidably mounted on the eccentric member, means to rotate the eccentric member relatively to the tube and a detachable clip member carrying a tube adapted to engage the tube portion on the eccentric member.

2. A curler comprising a cylindrical tube formed with jaws at one end, a member eccentrically mounted in the tube and rotatable about the axis thereof to grip a tress of hair placed between said jaws to enable the hair to be curled on the tube, means to rotate the eccentric member relatively to the tube, a clip member, and means carried by the clip member to detachably engage the eccentric member so that the clip member may be detached to retain the curl when the latter is separated from the tube.

3. A curler comprising a cylindrical tube, said tube being cut away at one end to form open jaws, a member rotatably mounted in the other end of said tube, said rotatable member carrying a spigot projecting from the tube, a knob fixed to said spigot whereby said member can be rotated, a rod eccentrically mounted in the rotatable member and extending through the cylindrical tube, a tubular member slidable along the rod and a clip member carrying a tube adapted to engage the tube on the eccentric member to detachably connect the tube and clip member.

4. A curler comprising a cylindrical tube, said tube being cut away at one end to form open jaws, a member rotatably mounted in the other end of said tube, said rotatable member carrying a spigot projecting from the tube, a knob fixed to said spigot whereby said member can be rotated, a rod eccentrically mounted in the rotatable member and extending through the cylindrical tube, a tubular member slidable along the rod, a clip comprising a pin, a clamping member and means for maintaining said pin and said clamp in co-operative gripping relationship and a tube fixed to the end of said pin adapted to engage the tube carried by the rod in the cylindrical tube to detachably connect the tube and clip.

5. A curler comprising a cylindrical tube, said tube being cut away at one end to form open

jaws, a member rotatably mounted in the other end of said tube, said rotatable member carrying a spigot projecting from the tube, a knob fixed to said spigot whereby said member can be rotated, a rod eccentrically mounted in the rotatable member and extending through the cylindrical tube, a tubular member slidable along the rod, a clip comprising a pin, a clamping member, a hinge between the pin and the clamping member, means to maintain the pin and the clamping member in gripping relationship whilst permitting said pin and said clamping member to be turned about said hinge into an open position of the clip and a tube fixed to the end of said pin adapted to engage the tube carried by the rod in the cylindrical tube to detachably connect the tube and clip.

6. A winding device for a curler comprising a cylindrical tube formed with jaws at one end, a member eccentrically mounted in the tube and rotatable about the axis thereof between the jaws, a tube portion slidably mounted on the eccentric member to detachably engage a hair clip, and means to rotate the eccentric member relatively to the tube.

7. A winding device for a curler comprising a cylindrical tube, said tube being cut away at one end to form open jaws, a member rotatably mounted in the other end of said tube, said rotatable member carrying a spigot projecting from the tube, a knob fixed to said spigot whereby said member can be rotated, a rod eccentrically mounted in the rotatable member and extending through the cylindrical tube and a tubular member slidable along the rod to detachably engage a hair clip.

8. A clip comprising a pin, a clamping member, means for maintaining said pin and said clamping member in co-operative gripping relationship, and a tube coaxially fixed to the end of said pin, for the purpose of detachable engagement with a suitable hair curler.

9. A clip comprising a pin, a clamping member, a hinge between the pin and the clamping member, means to maintain the pin and the clamping member in gripping relationship whilst permitting said pin and said clamping member to be turned about said hinge into an open position of the clip and a tube coaxially fixed to the end of said pin, for the purpose of detachable engagement with a suitable hair curler.
